UNITED STATES PATENT OFFICE.

HENRY M. DIXON, OF NEW YORK, N. Y.

PIPE-CLAMP.

SPECIFICATION forming part of Letters Patent No. 288,035, dated November 6, 1883.
Application filed April 6, 1883. (No model.)

To all whom it may concern:

Be it known that I, HENRY M. DIXON, of the city, county, and State of New York, have invented a new and useful Improvement in Pipe-Clamps, of which the following is a full, clear, and exact description.

Reference is to be had to the accompanying drawings, forming part of this specification, in which similar letters of reference indicate corresponding parts in all the figures.

Figure 1 is a plan view of my improvement, part being broken away. Fig. 2 is a side elevation of the same, partly in section. Fig. 3 is a sectional elevation of a part of the same, taken through the line $x-x$, Fig. 1. Fig. 4 is a sectional plan view of one of the standards, and showing the lower part of one of the clamping-arms. Fig. 5 is a perspective view of the lower part of one of the clamping-arms.

The object of this invention is to provide convenient clamps for holding pipes while "wiping" their joints.

The invention consists in a pipe-clamp constructed with a slotted base, and slotted right-angled standards secured to the base adjustably by bolts. The slotted right-angled standards have jaws upon their upper ends, and ratchet-teeth upon their outer sides, and to them are secured, by screw-bolts, the lower ends of curved arms, having at their upper ends hand-screws carrying swiveled jaws, so that pipes of different sizes can be firmly held, as will be hereinafter fully described.

35 A represents the base-plate, which is made of convenient length and breadth, and has three parallel longitudinal slots, B, formed in it, to receive the bolts C, that clamp the standards D to the said base-plate. The standards D are bent at right angles, and their lower parts that rest upon the bed-plate A, have longitudinal slots E formed in them to receive the fastening-bolts C, so that by loosening the nuts of the said bolts C the standards D can be readily adjusted as may be required. The upper ends of the standards D have wide jaws F formed upon them, which are recessed upon the upper side, to form seats for the pipe while being operated upon. The upright arms of

the standards D have longitudinal slots G 50 formed in them, and have ratchet-teeth H upon their outer sides, with which engage teeth I, formed upon the inner sides of the lower ends of the arms J. The lower ends of the arms J are secured to the standards D by 55 screw-bolts K, the teeth H I preventing the said arms from slipping while holding the pipe. The arms J are curved, as shown in Fig. 2, to bring their upper ends directly over the upper ends of the standards D. In the 60 upper ends of the curved arms J are formed screw-holes to receive the hand-screws L, to the lower ends of which are swiveled clamping-jaws M. The jaws M are recessed upon their lower sides to receive and fit upon the 65 pipe to be held. The recesses of the clamping-jaws F M are made angular, as shown in Fig. 2, so that they will fit upon and firmly hold different sizes of pipe.

When a joint is to be formed upon a straight 70 pipe, only two of the standards D and their attachments will be required. When a faucet is to be applied to a pipe, or a three-armed joint is to be formed, three of the standards D will be needed, and when a four-armed joint 75 is to be formed all four of the standards D will be used.

In using the clamp, the arms J are adjusted as the size of the pipe to be operated upon may require, and the hand-screws L are turned 80 up. The pipe is then laid upon the clamping-jaws F, and the hand-screws L are turned down, bringing the jaws M down upon the pipe and holding it firmly until the joint has been formed.

Having thus described my invention, what I claim as new, and desire to secure by Letters Patent, is—

1. A pipe-clamp constructed substantially as herein shown and described, and consisting of the slotted base A, the slotted right-angled standards D, having jaws F, the curved arms J, and the hand-screws L, and swiveled jaws M, as set forth.

2. In a pipe-clamp, the combination, with 95 the slotted base A, of the slotted right-angled standards D, having jaws F, and the bolts C, substantially as herein shown and described,

whereby the said standards can be adjusted to properly support the pipe, as set forth.

3. In a pipe-clamp, the combination, with the slotted standards D, having teeth H, and jaws F, of the curved arms J, having teeth I, and the screw-bolts K, the hand-screws L, and the swiveled jaws M, substantially as herein

shown and described, whereby the clamp can be adjusted to hold different sizes of pipe, as set forth.

HENRY M. DIXON.
